LOG BARKER WITH VANE-ACTUATED BARKING ARMS

George E. Robbins, Tacoma, Wash., assignor to Nicholson Manufacturing Company, Auburn, Wash., a corporation of Washington

Filed Nov. 30, 1959, Ser. No. 856,230
5 Claims. (Cl. 144—208)

This invention relates to log barkers of the rotary ring type and in particular to such barkers having barking arms swung by vane-type actuators. The barker in general is similar to the log barker disclosed in the prior Patent No. 2,802,495.

The principal object of the present invention is to simplify the mechanism for swinging barking arms which may be pivotally mounted on a rotary barking ring through which the logs to be barked are fed axially and nonrotatively. Specifically it is an object to swing such arms by pneumatic actuators of the vane type which include vanes swingable about the same axes as the barking arms.

Another object is to provide such vane-type actuators for barking arms which will be lighter and more compact than the actuators previously used for swinging such arms and which, in addition, will have fewer parts than previous actuators for this purpose. Consequently, the expense of construction and maintenance problems are considerably reduced.

In providing vane-actuated barking arms it is a further object to mount the actuators so that they can be adjusted relative to the barking ring for altering the range through which the barking arms can be swung relative to the barking ring by such actuators.

It is also an object to provide an effective seal for the vane of the actuator.

The aforesaid objects of the present invention can be accomplished by providing vane-type actuators for the barking arms which include vanes integral with the respective barking arms swingable about the barking arm pivots and extending outwardly from such pivots generally oppositely to the barking arms extending inwardly from such pivots. These vanes are received in sector-shaped housings which are mounted for swinging about the axes of the barker arms for angular adjustment to vary the range through which the barking arms can swing. Air under pressure is supplied to such vane housings for the purpose of swinging the vanes to press them into engagement with a log to be barked. A unitary strip of resilient elastomer material is received in a groove in the edge of the vane having a height in cross section when in the vane edge groove slightly greater than the depth of such groove and which strip has at least one groove extending lengthwise of its inner edge to enable such edge to be spread against the groove sides to seal the vane edges.

FIGURE 1 is an elevation view of the log barker viewed from the outfeed side of the rotatable barking tool mounting ring.

FIGURE 2 is a fragmentary sectional view through supporting structure of the barker taken on line 2—2 of FIGURE 1.

FIGURE 3 is a fragmentary sectional view taken on line 3—3 of FIGURE 2.

FIGURE 4 is a detail sectional view of an edge portion of the vane in a plane extending transversely of the vane, and FIGURE 5 is a similar view showing parts in exploded relationship.

FIGURE 6 is an enlarged detail sectional view through a portion of the vane housing.

The general assembly of the log barker is similar to that of prior Patent No. 2,802,495 mentioned above in

2

that the barker includes a ring 1 mounted for rotation in a stationary ring 2, which is supported by slides 3 carried by opposite ends of an upper cross beam 4 and a lower cross beam. These slides engage upright guides 5 along which the slides may be moved by frame supporting rods 6 so as to adjust the elevation of the ring 1 to center its opening 7 relative to a log L the underside of which is supported by carrier mechanism which is not adjustable in elevation. The ring 1 carries sprocket teeth 8 with which a chain 9 is engaged to rotate the ring during a log barking operation.

The rotary barking ring 1 is supported for rotation by circumferentially spaced arcuate shoes 10 tiltably mounted on ball and socket supports 11 which can be adjusted radially by threads 12 and locked firmly in the proper adjusted position by lock nuts 13.

On the rotary ring 1 are mounted barking arms 14 respectively swingable about the axes of pivots 15 which are spaced circumferentially of the ring. The number of arms utilized may differ in different barkers, four such arms being shown in the Patent No. 2,802,495 and five such arms being provided in the barker shown in FIGURE 1. A greater number of arms can be provided in barkers of the present design than for barkers utilizing the structure shown in such prior patent because of the more compact character of the arm-swinging actuators. The arms 14 are inclined inwardly from the pivots 15 in directions such that the barking tools 16 trail behind respective radial lines passing through the axis of the log being barked and the respective pivot axes of the arms. The degree of inclination of these arms during a barking operation will vary depending upon the size of the log being barked.

Integral with each swingable barking arm 14 and projecting outwardly from the barking arm pivot 15 is a vane 17 disposed in a plane parallel to the rotative axis of the barking ring and extending radially of the arm pivot. Consequently, this vane in each instance will swing conjointly with the swinging of the arm and through a corresponding angle. Each vane is received in a housing 18 having parallel side walls 19 of sector shape and outwardly flaring end walls 20 and 21 shown in FIGURE 3. These side walls are spaced apart a distance approximately equal to the width of the vane 17 and the end walls are inclined generally radially of the arm pivot 15 and are disposed at an angle approximately equal to the total possible angular movement of the vanes 17. The outer side of the housing is formed by an arcuate wall 22 which bridges between the outer ends of the side walls 19 and the end walls 20 and 21. A cylindrically arcuate wall 23 concentric with the axis of pivot 15 joins the inner ends of the end walls 20 and 21 and bridges between the inner portions of the side walls 19.

The inner portion of each vane housing is received within a V-shaped notch 24 of the ring 1, the opposite sides of which are disposed in planes parallel to the axis of the corresponding pivot 15 and which diverge at an angle greater than the angle of divergence of the housing walls 20, 21. The housing 18 can therefore rock within the notch 24 and about the axis of pivot 15 to vary the circumferential position of the housing about such axis for the purpose of adjusting the position of the angular range through which the vane 17 can swing. Consequently, the position of the swingable range of the corresponding arm 14 is varied for the purpose of adjusting the positions of closest approach of the barking tools 16 as the arms swing inward. Because of such availability of circumferential adjustment of the housings 18, it is not necessary for such housings to be of an arcuate extent to enable the vanes 17 to move within them for enabling the arms to swing between their maximum out-

ward positions and their minimum inward positions. If the machine is used customarily to bark small logs, the housings will be adjusted to enable the barking arms to swing inward so that the barking tools can almost touch. On the other hand, if large logs are customarily barked by the machine, the housings 18 can be adjusted circumferentially so that the arms 14 can swing into a position enabling the tools 16 to be retracted outward to clear the aperture through the barking ring.

It is, of course, necessary to provide mechanism for holding each housing 18 firmly in its circumferentially adjusted position. For this purpose ears 25 are provided on opposite sides of the housing to which bolts 26 are pivotally connected. At the opposite sides of the notches 24 lugs 27 are provided, recessed to receive cross-pins 28 of collars 38 slidable on the bolts 26. These collars are held in the desired adjusted positions by lock nuts threaded on the bolts at opposite sides of the collars as shown in FIGURE 3. These lock nuts can be adjusted on the screws at opposite sides of each housing so that the cross-pins carried by the opposite bolts seat firmly in the recesses of the lugs 27 to hold the housing against rocking around the axis of the corresponding pivot 15.

The vane 17 forms a partition between opposite end portions of its casing 18 so that a differential air pressure can be established at opposite sides of the vane for the purpose of exerting a swinging force on the vane and, consequently, on the arm integral with the vane. In order to enable such differential pressures to be established it is necessary to provide a suitable seal between the edges of the vane 17 and the interior of the housing. A satisfactory seal for the edge of the vane is shown in FIGURES 4 and 5. The seal structure includes a central strip 29 of elastomer material such as neoprene received in a groove having an imperforate bottom 30 formed in the edge of the vane. In its relaxed condition in the vane edge groove, as shown in FIGURE 4, the strip has a height in cross section slightly greater than the depth of such vane edge groove. It is desirable to provide recesses 31 in opposite sides of the strip to receive stiff backing rings 32 to prevent appreciable squashing out of the strip edge. Such backing rings are made of plastic or metal, preferably having bearing characteristics, such as the plastic Teflon. The recesses at opposite sides of the strip 29 are sufficiently wide so that most of the width of each ring 32 is received within its recess 31 of the vane as shown in FIGURE 4. This type of seal construction is provided along both longitudinal edges and across the end of the vane. The inner side of each strip may have one or more grooves 33 extending lengthwise of it so that if air attempts to by-pass the seal strip through the groove 30 air passing from the opening of such vane edge groove between one vane edge groove side and the adjacent side of the seal strip to the bottom of such vane edge groove and entering such strip grooves will spread the edge portions of the inner side of the strip to press them tightly against the sides of the vane edge groove 30 to prevent such air leakage.

The inner end of the vane 17 is integral with a hub 34 through which the pivot 15 passes to form an axle for the vane. The vane has been described as being integral with the barking arm 14 and this is true in the sense that the vane and barking arm constitute a single swingable unit in each instance. Such unit, however, is composed of a number of assembled parts which are secured together in fixed relationship. Thus the vane 17 and arm 14 actually are separately secured to the pivot member or axle 15 which is journaled by bearings 35 in the housing 18. The hub 34 is secured to the axle by a key 34' and the bearings 35 fit on shouldered portions of the axle as shown in FIGURE 2 to prevent axial movement of the vane. Sealing means are provided between such hub and the housing in the form of O-rings 36 which encircle the opposite ends of the hub and bear against the inner periphery of the cylindrically arcuate wall 23.

These O-rings are connected by a rod 37 of rubber material which forms a seal between the hub 34 and the portion 23 of the housing extending parallel to the axis of the pivot 15. Such sealing means serves both to prevent leakage of air from the vane housing past the ends of the hub 34 and also prevents leakage from one side of the vane to the other around the hub 34. The rod 37 may be received in a groove extending lengthwise of the hub as shown in FIGURE 3.

The outer ends of the axle are splined and fit complementally splined collars 38 having projections 39 which are bolted and keyed or otherwise suitably secured to the root portion of the barking arm 14, as shown in FIGURE 2. The outer peripheries of these collars constitute trunnions journaled in the barking ring 1 to support the vane and its housing. The angular relationship between the blade and the arm can be selectively altered by shifting the rotative positions of the collars 38 on the splined ends of the pivot axle 15 in increments corresponding to the coarseness of the splined connections. It will be evident that the vane and arm can be suitably secured to their pivot in various ways.

During rotation of the ring 1 in the direction indicated by the arrow in FIGURE 1, the centrifugal force acting on the arms 14 will tend to swing the tools 16 outward so that the arms and vanes rotate about their pivots 15 in a counterclockwise direction to prevent the vanes 17 from striking the end walls 21 of the casings 18 by such action. Consequently, it is necessary to supply a positive force to swing the arms inward and hold the barking tools firmly against the log to effect barking. Such pressure is produced by supplying fluid under pressure to the housing 18 for the purpose of pressing vane 17 in a direction to swing the tool arm inward.

It will be evident that when a log moving through the barking ring passes beyond the tool arm the force of the air acting on the vane 17 will swing the arms inward abruptly as the tools 16 ride off the end of the log. It is, therefore, desirable to provide snubbing or cushioning mechanism for the purpose of arresting the movement of the vane and arm so that the vane will not be driven forcibly against the wall 21 of the housing. Such cushioning mechanism is shown in FIGURES 3 and 6 as including a cylinder 40 having a threaded neck 41 which is screwed into a threaded port in the end wall 21 of the housing 18. The end of the cylinder 40 opposite the neck 41 is closed by a removable threaded plug 42. In this cylinder is slidably received a plunger 43 which has been inserted through the end of the cylinder closed by the plug 42. This plunger includes an elongated portion which fits slidably in the bore of the neck 41 and the portion of the plunger within the cylinder includes an annular rib 44 which slidably engages the inner wall of the cylinder and a reduced or shouldered end portion 45. A spring 46 received in the cylinder has one end bearing on the shouldered portion 45 of the plunger 43 and its other end bearing on the plug 42 to urge the plunger into the housing 18 as far as possible.

On the side of vane 17 adjacent to the end wall 21 of the housing is a pad 17' of rubber material located in position to engage the end of the plunger 43 as the vane swings toward the end wall 21 to the position of FIGURE 6. Inward swinging of the barking arm 14 effected by the pneumatic pressure on vane 17 would continue to move the vane from the position of FIGURE 6 toward the position of FIGURE 3 which would force the plunger 43 to the left as seen in these figures opposed by the force of spring 46. When the plunger 43 is in the position shown in FIGURE 6, the port 47 through the wall of the plunger is in registry with the port 48 in the wall of the cylinder 40. The port through the wall of the plunger communicates with the hollow bore 49 extending throughout the length of the plunger and communicating with the portion of the housing 18 between the wall 21 and the vane. Consequently, this portion of the housing is in

communication with the atmosphere through the bore 49 and registering ports 47 and 48 until the pad 17 begins to press the plunger 43 to the left as seen in FIGURE 3. Thereupon, the plunger port 47 will be moved out of registry with the cylinder port 48 so that the air remaining in the housing 18 between the vane 17 and the housing wall 21 will be compressed progressively to cushion further movement of the vane toward the wall 21. Such compression of the air will provide a snubbing action which will prevent the vane 17 being stopped abruptly and producing a shock as the barking arms 14 are forced inwardly as the log passes beyond them.

It will be evident that air may be supplied to the rotary ring 1 and the vane housing 18 in various ways. The particular construction shown in FIGURE 2 is representative. Air is supplied by pipe 50 to a passage 51 in the barking ring supporting structure from which it passes through a seal 52 to the pipe 53. This pipe is connected to the hose 54 which in turn is connected to wall 20 of the vane casing 18. The pressure of the air supplied may be varied by manipulation of the pressure control valve 55 so that the force exerted on the vane 17 can be altered to change the pressure of the barking tool 16 on the log.

I claim as my invention:

1. In a rotary ring log barker, an arm projecting from the ring inwardly, pivot means mounting said arm on the ring for swinging of its inner end about an axis extending parallel to the axis of the ring, a housing carried by said ring adjacent to said pivot means and having end walls disposed respectively in planes substantially parallel to the axis of said pivot means, a vane slidably fitted in said housing and connected to said arm for swinging therewith relative to said housing about the axis of said pivot means, means for supplying fluid under pressure to said housing between said vane and one of said end walls for swinging said vane in a direction to urge said vane toward the opposite end wall and the swinging end of said arm inwardly, and combined venting and pneumatic snubbing means carried by said opposite end wall and including a cylinder having a vent aperture therein and a plunger received in said cylinder, movable relative to such vent aperture and engageable by said vane to be moved thereby into position closing such aperture for snubbing swinging of said vane toward said opposite end wall.

2. A log barker comprising a rotary ring, an arm projecting from said ring inwardly, pivot means mounting said arm on said ring for swinging of its inner end about an axis extending parallel to the axis of said ring, said ring having a notch receiving and flaring outwardly from said pivot means, a housing of substantially sector shape having an angular extent less than the angular extent of such notch, received within such notch, means rockably guiding said housing for adjustment within such notch about the axis of said pivot means, anchor means interconnecting said ring and said housing for securing said housing relative to said ring in a selected adjusted position, a vane slidably fitted in said housing and connected to said arm for swinging therewith relative to said housing about the axis of said pivot means, and means for supplying fluid under pressure to said housing for swinging said vane in a direction to urge the swinging end of said arm inwardly.

3. In a rotary ring log barker, an arm projecting from the ring inwardly, pivot means mounting said arm on the ring for swinging of its inner end about an axis extending parallel to the axis of the ring, a housing carried by the ring, a vane separate from said arm slidably fitted in said housing, disengageable means including one member carried by said arm and a separate member carried by said

vane connectible in different angular relationships for fastening together said vane and said arm in a predetermined relationship selected from a plurality of such different possible angular relationships for swinging of said vane and said arm relative to said housing about the axis of said pivot means, means supporting said housing for angular adjustment relative to said ring, and means for supplying fluid under pressure to said housing for swinging said vane and said arm.

5 4. In a rotary ring log barker, a rotating ring, an arm projecting from said ring inwardly, pivot means mounting said arm on the ring for swinging of its inner end about an axis extending parallel to the axis of the ring with said arm disposed at one side of the radius of said ring through 10 said pivot means axis so that the action of centrifugal force on said arm as said ring rotates tends to swing said arm outward, a housing carried by said ring, a vane slidably fitted in said housing and connected to said arm for swinging therewith relative to said housing about the axis 15 of said pivot means, and pressurized gas supply means connected to said housing maintaining gas in said housing under pressure at such side of said vane as will effect pressure on said vane in a direction to urge said arm inward in opposition to centrifugal force acting thereon and to follow depressions in the surface of a log and to hold said arm pressed against the log irrespective of outward swinging movement of such arm caused by its engagement with 20 projections on the surface of such log.

25 5. In combination, an arcuate housing, a vane in said 30 housing having an edge slidable relative to a wall of said housing, the edge of said vane having a groove extending lengthwise thereof, opening toward said housing wall and having an imperforate bottom, and a unitary strip of resilient elastomer material received in such vane edge 35 groove, having a height in cross section when in such vane edge groove slightly greater than the depth of such vane edge groove and said elastomer material strip having groove means extending lengthwise of its inner edge to enable such inner edge to be spread by fluid under pressure 40 passing from the opening of such vane edge groove between one vane edge groove side and the adjacent side of said strip to the bottom of such vane edge groove, the width of said resilient elastomer strip being sufficiently 45 nearly equal to the corresponding width of said vane edge groove that such spreading of such strip groove means presses the strip sides against the sides of such vane edge groove.
